F. W. BAUMANN

RAIL ANCHOR

Filed Jan. 3, 1925

FIG. 1

FIG. 2

FIG. 3

FIG. 4

INVENTOR

Frederick W. Baumann
By Ray, Stoten & Martin
Attorneys

UNITED STATES PATENT OFFICE.

FREDERICK W. BAUMANN, OF PITTSBURGH, PENNSYLVANIA, ASSIGNOR TO OLIVER IRON & STEEL CORPORATION, OF PITTSBURGH, PENNSYLVANIA, A CORPORATION OF PENNSYLVANIA.

RAIL ANCHOR.

Application filed January 3, 1925. Serial No. 374.

To all whom it may concern:

Be it known that I, FREDERICK W. BAUMANN, a citizen of the United States, and resident of Pittsburgh, in the county of Allegheny and State of Pennsylvania, have invented a new and useful Improvement in Rail Anchors; and I do hereby declare the following to be a full, clear, and exact description thereof.

10 My invention relates to rail anchors and particularly to those devices of the type adapted to be secured to railway rails and to bear against the sides of the cross ties to prevent creeping of the rails.

15 One object of my invention is to provide a device of simple form and which may be cheaply made.

Another object of my device is to provide an anchor which may be composed substantially entirely of rolled steel plates blanked from stock material by dies, at one punching operation.

20 Still another object is to provide a unitary structure that may be marketed and freely handled without the parts becoming misplaced or lost.

25 A further object of my invention is to provide a rail anchor of simple and cheap construction which will grip and hold the edges of the rail base with increased force upon the application of creeping strain.

30 Some of the forms which my invention may take are shown in the accompanying drawing, wherein Fig. 1 is an elevational view of a portion of a railroad rail showing one stage of the application of the anchor to the rail; Fig. 2 is a similar view showing the anchor completely in place; Fig. 3 is a plan view of the device of Fig. 2, and Fig. 4 is a plan view of a modified form of anchor.

35 The anchor is shown as applied to a fragmentary portion of a railroad rail 5, and comprises two plates 6 that are preferably secured together at one end by a rivet or bolt 7 and at their other ends are perforated to receive a pin 8 that serves as a pivot for a clip or dog 9. The pin 8 is enlarged at its mid-portion so as to form shoulders against which the inside faces of the plates 6 bear. The pin 8 therefore serves not only as a pivot for the clip 9, but acts as a spacer for holding the adja-

cent ends apart, to prevent them bearing against the clip 9 and interfering with the manipulation thereof.

40 The pin 8 and the clip 9 are held in place either by simply bringing the ends of the plates into position over the reduced ends of the pin, or the ends of the pin may be upset. The structure is therefore unitary and all parts are always in assembled position, ready for use.

45 The plates 6 are preferably cold stamped from rolled steel and provided with projections 10, that are inclined on their lower edges to closely fit the upper surface of the rail base. The upper edges of the body portion of the plates 6 are cut away slightly as indicated at 6^a, so that when the anchor is locked in position as shown in Fig. 2, the parts are all maintained under tension. The plates are also provided with projections 11 for engaging and gripping one edge of the rail base. The projections 50 10 are undercut a distance sufficient to permit driving of the plates endwise against the edge of the rail base and cause the projections to grip the rail base. Furthermore, the cut out portion permits the anchor to adapt itself to rail bases of various widths.

55 Before the clip 9 is driven inward from the position shown in dotted lines in Fig. 2 to that shown in full lines, the plates 6 are moved laterally of the rail until the projections 10 grip the rail base. The inner vertical edge of the edges of the projections 11 are then brought into engagement with the rail base at its other edge.

60 The forcing of the clip 9 to locked position closes the gap at 6^a, since the plates will yield somewhat, thus providing tension for tightly holding the clip in place. The shortest radius of the clip 9 with respect to its pivotal axis is approximately 65 at the point 12, so that as the clip is driven from the position indicated in dotted lines in Fig. 2 to that indicated in full lines, an over-the-center action is secured that assists in maintaining the clip against accidental 70 displacement from its locking position.

75 In Fig. 4 I show an anchor provided with side members 6^b that are formed integrally, from a single bar of metal, instead of separately as in Fig. 3. The outer end of this 80 form of clip is offset slightly to permit of

the binding effect under creeping strains above referred to. In both this form of device and the form shown in Fig. 3, the gripping lugs are offset in a direction longitudinally of the rail, so that when the plates are lying against the tie and creeping strains are imposed thereon, there will be a tendency for the anchor to twist and grip the edges of the rail base more firmly.

10. I claim as my invention:

1. A rail anchor comprising gripping plates for transverse disposition beneath a rail and each provided with an overhanging rail base gripping jaw at one end, and at 15 its other end with a vertically disposed gripping jaw, the plates being secured together at their first named ends, and at their other ends provided with means for supporting a rail-engaging clip.

20. 2. A rail anchor comprising gripping plates for transverse disposition beneath a rail and each provided with an overhanging rail base gripping jaw at one end and at 25 its other end with a vertically disposed gripping jaw, the plates being secured together in flatwise engagement at one end and spaced apart at their other ends.

30. 3. A rail anchor comprising gripping plates for transverse disposition beneath a rail and each provided with an overhanging rail base gripping jaw at one end and at 35 its other end with a vertically disposed gripping jaw, the plates being secured together in flatwise engagement at one end and spaced apart at their other ends, a pivot pin extending across the last-named space, and a locking clip supported by said pin.

40. 4. A rail anchor comprising plates having longitudinally disposed gripping jaws adjacent to one end thereof and vertically disposed gripping jaws adjacent to their other ends, the first-named gripping jaws being undercut so that the distance between the rear wall of said undercut portion and 45 the inner vertical wall of the second named gripping jaws is greater than the normal width of the rail bases with which the anchor is to be employed, and the first-

named gripping jaws having longitudinally inclined gripping surfaces.

50. 5. A rail anchor comprising gripping plates secured together at one point but spaced apart at one end, aligned perforations extending through the plates at said end, a pin extending through said perforations and secured to said plates, and a movable clip member carried by said pin.

60. 6. A rail anchor comprising gripping plates secured together adjacent to one end and spaced apart adjacent to their other ends, aligned perforations extending through said last-named ends, and a pin having reduced end portions seated within said perforations and an enlarged mid-portion disposed between the plates to serve as a spacer therefor.

7. A rail anchor comprising gripping plates secured together adjacent to one end and spaced apart adjacent to their other ends, aligned perforations extending 70 through said last-named ends, a pin having reduced end portions seated within said perforations, an enlarged mid-portion disposed between the plates to serve as a spacer, and 75 a clip member pivotally connected to said mid-portion of the pin.

8. A rail anchor comprising plate-like portions secured together at one end and whose upper edges are adapted to engage the underside of a rail, a longitudinally inclined gripping jaw on said portions, for gripping the top surface of the rail flange adjacent to said end, a vertically extending jaw at the other end of said plates in position to engage the adjacent edge of the rail base, and a locking member for maintaining said vertical jaw in operative position, the distance between the base of said first named gripping jaw and the inner face of the second named jaw being greater than the normal width of the rail bases with which the anchor is to be used.

In testimony whereof I, the said FREDERICK W. BAUMANN, have hereunto set my hand.

FREDERICK W. BAUMANN.
